UNITED STATES PATENT OFFICE.

JOSEPH P. BUDD, OF EVERETT, WASHINGTON.

DESIGN FOR A HOLDBACK LOOP AND GUARD.

SPECIFICATION forming part of Design No. 35,175, dated October 8, 1901.

Application filed August 29, 1901. Serial No. 73,762. Term of patent 3½ years

To all whom it may concern:

Be it known that I, JOSEPH P. BUDD, a citizen of the United States, residing at Everett, in the county of Snohomish and State of Washington, have invented and produced a certain new and original Design for Holdback Loops and Guards; and I do declare the following to be a full, clear, and exact description of the invention, such as will enable others skilled in the art to which it appertains to make and use the same.

This invention relates to a design for a holdback loop and guard and is illustrated in the accompanying drawings, in which—

Figure 1 is a bottom plan view of a combined holdback loop and guard embodying the design, and Fig. 2 is a side elevation of the same.

The leading features of the design consist, as shown, of a bar 1, having at one end a loop 20 or eye 2 and at the other end a lateral arm 3, terminating with a lug or ear 4. The bar is provided at intervals with perforations 5 and is notched or recessed in its side edges to form scallops 6.

Having thus described my invention, what I claim is—

The design for a holdback loop and guard, substantially as herein shown and described.

In testimony whereof I have hereunto set 30 my hand in presence of two subscribing witnesses.

JOSEPH P. BUDD.
